UNITED STATES PATENT OFFICE

130,049

DESIGN FOR A TEXTILE FABRIC

Leo Schechter, New York, N. Y.

Application September 17, 1941, Serial No. 103,385

Term of patent 3½ years

To all whom it may concern:

Be it known that I, Leo Schechter, a citizen of no country, residing in New York city, county of New York, and State of New York, have invented a new, original, and ornamental Design for a Textile Fabric, of which the following is a specification, reference being had to the accompanying drawing, forming part thereof, wherein the figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric, substantially as shown, and described.

LEO SCHECHTER.
